UNITED STATES PATENT OFFICE.

SERENUS M. COLBURN, OF MINNEAPOLIS, MINNESOTA, ASSIGNOR OF ONE-HALF TO
FREDERICK KEEES, OF MINNEAPOLIS, MINNESOTA.

DESIGN FOR A STREET-LIGHT STANDARD.

44,056.

Specification for Design.

Patented May 20, 1913.

Application filed March 17, 1913. Serial No. 755,043. Term of patent 7 years.

To all whom it may concern:

Be it known that I, SERENUS M. COLBURN, a citizen of the United States, residing at Minneapolis, in the county of Hennepin and State of Minnesota, have invented a new, original, and ornamental Design for a Street-Light Standard, of which the following is a specification, reference being had to the accompanying drawing, forming part thereof.

The single view of the drawing is a side elevation of a street light standard embodying the improved design.

I claim:

The ornamental design for a street light standard as shown.

SERENUS M. COLBURN.
